CLOSURE OPERATOR

Filed April 2, 1931

UNITED STATES PATENT OFFICE

EARL Y. GILKEY, OF EAST SYRACUSE, NEW YORK

CLOSURE OPERATOR

Application filed April 2, 1931. Serial No. 527,298.

The present invention relates to window constructions, particularly to the type of window comprising essentially a frame and sash and in which the sash is mounted for 5 swinging movement relatively to the frame in moving from closed to open position and vice versa.

The invention contemplates the combination, with a frame and movable sash, of 10 means whereby the opening and closing movements of the sash may be performed with facility and, if desired, from a remote point.

In accordance with the invention, the window sash is provided with locking means 15 adapted to engage the frame when the window is in closed position, to secure the same in such position, and connected to this locking means and also operatively associated 20 with the sash and frame is a flexible element, such as a cord or chain, which extends to a point within reach of an operator. When this flexible element is placed under tension, the locking means is first released, and, upon 25 continuation of the tension, the flexible element is caused to act on the sash in such manner as to initiate its opening movement.

Preferably the sash is so designed and constructed and so mounted upon the frame 30 that, after being unlocked and partially opened, it moves into fully opened position by itself, under the influence of gravity. If desired also, the sash manipulating mechanism may be so designed as to render it useful in closing the sash as well as opening the same. The flexible element may be of such 35 length as to extend to a point remote from the window so that the window may be opened and closed without necessitating the presence of an operator near the same. This 40 is particularly desirable where the windows are elevated such distance above the floor of a building structure as to be comparatively inaccessible.

The invention may be adapted to various 45 types of windows of the general class in which the sash swings outwardly in its opening movement rather than moves or slides in the plane of the frame, and it will be understood that that form of the invention

herein described in detail and illustrated in the accompanying drawing is set forth by way of example only.

In the drawing:

Figure 1 is a vertical transverse section 55 through a window frame and sash embodying the invention;

Figure 2 is a partial side elevation of the window, showing the sash operating mechanism;

Figure 3 is a section on line 3—3 of Figure 2;

Figure 4 is a section on line 4—4 of Figure 3;

Figure 5 is a section on line 5—5 of Figure 4; and

Figure 6 is a section on line 6—6 of Figure 2.

In the drawing I have illustrated a metallic window, the members of the frame and sash being fabricated of structural steel members of well-known type, but it will be understood that the invention is in no wise limited to a window construction formed of any definite materials or in any specific 70 manner. In the window shown the frame is generally indicated at 10 and the sash at 11. When seated in the frame, the sash makes double contact with the frame entirely around its periphery in order to more effectively resist the passage of air, moisture, etc., which is an expedient well-known in the art. The vertical sash contacting members of the frame are provided with guides for sliding blocks, one of which is indicated at 12, and 75 to these blocks the upper edge of the sash is pivotally connected, as by pivots 13.

Links 14, positioned at the sides of the sash, are pivotally connected at their lower ends to the frame by pivot pins 15 and at 80 their upper ends to the opposite sides of the sash by pivots, one of which is indicated at 16. In the opening and closing movements of the sash the blocks 12 are constrained to move vertically in the guideways formed in 85 the frame, and hence the window must necessarily swing about the axis defined by pivots 13. The links 14 cause the lower edge of the window to be thrown outwardly as the upper edge thereof is brought downward so that, 90

when the window is fully opened, it occupies some position such as that shown in dotted lines in Figure 1 of the drawing.

In the case of the window sash shown, opening movement is completed solely by the pull of the operator upon the cord, but, if desired, the parts may be so arranged that the final opening movement is completed by gravity. The sash may be limited in its opening movement either by suitable stops for the slide blocks 12, chains, or other stop means, or by the action of links 14, it being apparent that these links themselves must necessarily lock the sash against further downward movement at some point in its travel in view of the fact that the upper edge of the sash is constrained to move in a vertical path.

Secured to a lower sash member indicated at 20 is a simple form of latch comprising a body or shell 21, latch bolt 22, and spring 23. The parallel side walls of the shell or body 21 are curved outwardly, as shown clearly in Figure 5, from the bottom of this shell to points near the top thereof, and the spring 23 is received within this generally cylindrical portion of the sash, the upper end of the spring seating against shoulders 25 of the shell and the bottom of the spring resting on the latch bolt, the latch bolt being provided with a rectangular aperture in which the spring is received. The spring is normally under compression and tends to throw the latch bolt downwardly. To the upper end of the latch bolt is secured a hook 26.

In Figure 1 the sash is shown, in full lines, in its closed position with the lower end of the latch bolt positioned behind a member secured to the window frame so that, in order to release the sash so that it may be moved to its open position, it is necessary to lift the latch bolt to disengage the frame member. The lower end of the latch bolt is inclined so that, when the sash is closed, this inclined edge may act as a cam surface, enabling the latch bolt to ride over the frame member with which it cooperates. Once over the frame member, it drops immediately into locking position, being rapidly projected by the spring 23. A cord, chain, or other flexible element is indicated at 27, and this flexible element has one end connected to the hook 26 and is guided by rollers so that it normally occupies the position shown in the drawing.

Secured to the frame member immediately below the position which the latch occupies when the sash is in closed position is a bracket, indicated at 28, upon which are rotatably mounted, respectively, a pair of guide rollers 29, 29', hereinafter designated the first guide, and another pair of guide rollers 30, 30', these pairs of guide rollers being laterally spaced as shown in Figures 2 and 6. Secured to the top of the sash and above the latch is a second bracket, indicated

at 31, in which is rotatably supported a guide roller 32. A third guide roller is indicated at 33, this guide roller being rotatably supported at its ends in spaced bracket members 34 mounted on the sash. Bracket members 34 are provided with flanges 34' which lie flat against flanges 21' of the latch body 21. By means of two screw bolts therefor, the latch body and both bracket members are secured to the lower sash member. It will be observed that a straight line connecting guide 29 and guide 32 passes between the latch and the third guide roller 33. The flexible element 27 thereof, which passes over all three of these guide rollers, when placed under tension, will tend to draw the third guide roller 33 into a position on a line intermediate the first and second guides.

In the operation of the device, and assuming that the operator exerts a pull on the flexible element, for instance at the point 35, the latch bolt 22 is first lifted so as to release the frame member, thus unlocking the sash. If the pull is continued, the lower end of the sash is moved outwardly by the action of the flexible element on roller 33, until roller 33 has been pulled into a position on a line connecting the first and second guides 29 and 32, respectively. When in this position, the lower sash member has been laterally displaced from its closed position above the associated frame member and the links 14 tilted outwardly so that the sash is free to swing downwardly somewhat in its opening movement. The pull upon flexible element 27 may be continued, if the sash itself is frictionally retarded or is not so mounted as to lower itself by gravity, so as to exert a continual downward pull upon the upper guide roller 32 and eventually bring the sash into the dotted-line position, Figure 1. The flexible element may then be released, and the window will remain in this position.

It will be observed that the flexible element 27 is looped beneath the guide roller 29, and its return reach passes upwardly and over guide roller 30', the end of this reach being secured to the sash. Assuming the attendant to exert a downward pull at 40, therefore, it will be apparent that the force applied by the flexible element to the lower edge of the sash will tend to draw this edge toward the frame. If the pull is continued, the sash will be returned to its closed position, the latch bolt riding over the lower edge of the frame and being snapped into locking position by spring 23. By the means disclosed, therefore, the sash may be both opened and closed.

In adapting the invention to windows of various types, the design and arrangement of its various component elements may be considerably varied, as will be apparent to one skilled in the art.

Having thus described the invention, what

is claimed as new and desired to be secured by Letters Patent is:—

In a window construction, in combination, a frame, a sash mounted on the frame for outward swinging movement relatively thereto about a horizontal axis adjacent its upper edge in moving from closed to open position and vice versa, a latch mounted on the inside of the sash adjacent its lower edge for engaging the frame to secure the sash in closed position, a guide on the frame adjacent the position which the latch occupies when the sash is closed, a second guide mounted on the sash adjacent the top thereof, a third guide mounted on the sash adjacent the latch and having its guide surface displaced laterally from a line connecting the first and second guides and on the opposite side of such line from the latch, and a flexible element connected to the latch and passing successively over the second, third, and first mentioned guides, said element, when placed under tension, releasing the latch and exerting a thrust on the third guide which tends to move the third guide to a position on the line connecting the first and second guides, thereby partially opening the sash.

In testimony whereof I hereunto affix my signature.

EARL Y. GILKEY.
